UNITED STATES PATENT OFFICE.

MARGARET COLVIN, OF INVERNESS, SCOTLAND.

DETERGENT.

1,074,491.

Specification of Letters Patent. Patented Sept. 30, 1913.

No Drawing.

Application filed April 28, 1913. Serial No. 764,067.

To all whom it may concern:

Be it known that I, MARGARET COLVIN, a subject of the King of the United Kingdom of Great Britain and Ireland, and residing at 5 Inverness, Scotland, have invented a certain new and useful Improvement in Detergents, of which the following is a specification.

This invention relates to a scouring, washing, cleansing, bleaching, purifying and toilet composition composed preferably of a mixture of citric acid, preferably in the form of the fresh juice of lemons, gelatin, paraffin wax, bran water, turpentine, infusions of orris-root and burdock root, and 10 soap. The said mixture is added in or about the proportions hereinafter specified to any variety of commercial soap while liquid and luke-warm in manufacture, or after the soap has been shredded and rendered 15 liquid and luke-warm by heat and water. Experiment has demonstrated that the addition of these ingredients to the saponaceous mass increases its cleansing and bleaching qualities, modifies its causticity and renders 20 it non-injurious to the finest textile fabrics, woolen, cotton, linen or silk, or to the most delicate human skin, while also serving to bulk the soap.

The following approximate proportions 25 give good results:

	1.5	fresh juice of lemons.
	4.0	gelatin dissolved in hot water.
35	1.0	paraffin wax melted.
	10.0	infusion, of $\frac{1}{2}$ pound bran to one quart water.
	1.0	infusion of 3 ounces orrisroot to one pint water.
40	1.0	infusion of 3 ounces burdock to one pint water.
	2.0	turpentine.

Composition. 20.5
Soap ----- 79.5
100.0

50 The ingredients just above stated are added to the soap while the latter is in a liquid or semi-liquid luke-warm state, and thoroughly incorporated by mixing. The 55 infusion of orris-root gives the soap a deli-

cate aroma, and this infusion has a softening or mollifying effect, as does also the infusion of burdock root. These infusions may, however, be omitted, if desired. The lemon juice tends to neutralize the alkalinity of the compound so that delicate fabrics will not be injured and delicate skins will not be roughened or injuriously affected, as also to assist in removing stains. The preparation is then made up in the usual way as 60 bars, tablets, pastes, creams, jellies, emulsions or otherwise—water being added as required for the different forms into which the composition may be made up for use.

For the finer toilet preparations it is preferred to use a superfatted soap with a basis of tallow and to add the other ingredients in substantially the same proportions in which these are added to the common soap, 70 the mixing and making up into convenient 75 forms for use being effected as above stated.

Having now described my invention what I claim and desire to secure by Letters Patent of the United States is:—

1. An improved detergent composed of 80 citric acid, gelatin, paraffin wax, bran water, turpentine and commercial soap, in substantially the proportions stated.

2. An improved detergent composed of 85 citric acid, gelatin, paraffin wax, bran water, turpentine, commercial soap and infusions of orris-root and burdock root, in substantially the proportions stated.

3. An improved detergent composed of about 79.5 parts of commercial soap, 1.5 90 parts citric acid, 4 parts gelatin, 1 part paraffin wax, 10 parts infusion of one half pound bran to one quart of water and two parts of turpentine.

4. An improved detergent composed of 95 about 79.5 parts of commercial soap, 1.5 parts citric acid, 4 parts gelatin, 1 part paraffin wax, 10 parts infusion of one half pound bran to one quart of water, two parts turpentine, 1 part infusion of 3 ounces orris-root to one pint of water, and 1 part infusion of 3 ounces burdock root to one pint of water.

In testimony whereof I have signed my name to this specification in the presence of 105 two subscribing witnesses.

MARGARET COLVIN.

Witnesses:

WALLACE CRANSTON FAIRWEATHER,
JOHN McCLEARY.
